UNITED STATES PATENT OFFICE.

JAY M. JOHNSON AND HUGO J. BAUR, OF CHICAGO, ILLINOIS; SAID BAUR ASSIGNOR TO SAID JOHNSON.

FARE-REGISTER.

1,159,772.

Specification of Letters Patent. Patented Nov. 9, 1915.

Application filed March 7, 1910. Serial No. 547,644.

To all whom it may concern:

Be it known that we, JAY M. JOHNSON and HUGO J. BAUR, citizens of the United States, and residents of the city of Chicago, 5 in the county of Cook and State of Illinois, have invented certain new and useful Improvements in Fare-Registers; and we do hereby declare that the following is a full, clear, and exact description of the same, 10 reference being had to the accompanying drawings, and to the numbers of reference marked thereon, which form a part of this specification.

Heretofore fare registers for street cars 15 and the like have sometimes been constructed to afford an audible signal for each fare collected and also to register the fare usually in view of the passenger. With such devices it is frequently possible for the conductor 20 or collector to defraud because of the inattention of the passenger to the audible and visible signal afforded. In consequence in many instances such devices have proven quite unsatisfactory. In other constructions 25 the fares are deposited and mechanically counted, the count of the number of fares being recorded upon a suitable mechanism therefor. This also may prove insufficient, inasmuch as it sometimes occurs that break- 30 age or a defect in the registering or counting mechanism, if known to the collector or conductor, enables him to defraud with impunity.

The object of this invention is to afford in 35 a fare register a double registering system with which, upon the deposit of the fare, an audible signal is produced and a register or count upon a concealed registering mechanism is made and thereafter a mechanical 40 count of the fares collected is made in the same register and the count registered, thus affording a certain double record of the fares collected.

It is also an object of the invention to 45 afford a construction by the use of which fares, when once deposited in the fare box, cannot be extracted except by the one authorized so to do, and also to afford a construction in which the deposited fare is at all 50 times in full view until the register of its receipt has been completed.

It is also an object of the invention to

afford mechanism whereby foreign objects delivered into the fare box may be rejected from the registering means. 55

The invention is shown in connection and in combination with a coin counting and registering mechanism such as set forth in our application for patent for "fare registers" executed Dec. 14, 1909, Serial No. 60 546,801.

The invention embraces many novel features and consists in the matters hereinafter described and more fully pointed out and defined in the appended claims. 65

In the drawings: Figure 1 is a view in front elevation of a device embodying our invention. Fig. 2 is a view in front elevation of the coin carrying wheel. Fig. 3 is a view in rear elevation of the frame plate, 70 showing the actuating means for the register. Fig. 4 is an enlarged vertical section of the fare box shown in Fig. 1. Fig. 5 is a side elevation of the coin chute showing the same removed from the fare box. Fig. 6 is 75 a view in elevation of a part of the chute. Fig. 7 is a section taken on line 7—7 of Fig. 4. Fig. 8 is an enlarged section on line 8—8 of Fig. 4. Fig. 9 is a view partly in plan and partly in section of a portion of the 80 fare registering mechanism. Fig. 10 is a section on line 10—10 of Fig. 9. Figs. 11 to 15 inclusive are sectional views of the actuating means for the fare box registering mechanism. Fig. 16 is a sectional view 85 taken on line 16—16 of Fig. 3 and showing the coin chutes in position. Fig. 17, is a section on line 17—17 of Fig. 3, with parts omitted. Fig. 18 is a section on line 18—18 of Fig. 17, with the frame plate omitted. 90 Fig. 19 is a face view of the coin chutes showing the same removed from the machine.

As shown in the drawings: A registering fare box is combined with a counting and registering fare register which may be of any preferred type, but which for convenience is illustrated as before described, as the counting and registering fare register embodying the aforesaid application for patent, and in which 1', indicates frame members, as shown, constructed in the form of right angled triangles and having the face or bearing surface thereof inclined at a 95 100

sufficiently steep angle of inclination for the purposes of the machine. Secured on the inclined faces of said frame members is a frame plate 2' on which the counting and registering mechanism is supported. Said frame plate 2', as shown, is countersunk upon its face to afford a recess of uniform depth in which is rotatably supported the coin carrying wheel whereby the coins are carried to counting position. Said carrying wheel is journaled on said frame plate 2', by means of a shaft 4', journaled in a central rearwardly and downwardly directed hub 5', and comprises a circular disk 6', integral with or otherwise rigidly secured on the shaft 4', to which is secured a rim 7', by means of screws or otherwise. Said rim comprises a relatively thin plate of metal conveniently steel, having pockets arranged in its periphery equal distances apart. As shown, each of said pockets is adapted to carry more than one size of coin. For this purpose, the bottom of the pocket is gummed or cut on an arc of a smaller radius than the outer portion of the pocket, thus permitting a large coin to be held considerably extended from the pocket and permitting a smaller coin to fall farther into the pocket and to project but a slight distance beyond the same at its edge. Keyed on said shaft 4', at the rear side of the frame plate is a worm gear 8', which meshes with a worm 9', secured upon the shaft 10'. Said shaft is the driving shaft of the machine and may be operated either manually or by means of a suitable motor, as desired, and by its rotation acts to continuously rotate the carrying wheel.

Adjustably secured by threading or otherwise upon the externally threaded hub or boss 5', of the frame plate, is an anti-friction bearing 11', on which is secured to rotate freely therewith, a spur gear 12' and a ratchet wheel 13', and mounted upon the frame plate at any convenient point is a spring pressed detent 14', the head of which at all times engages the ratchet wheel 13', above mentioned to hold said gear and ratchet from throwing inaccurately because of the momentum of the moving parts.

Journaled on the frame plate is an accumulating shaft 15', which is provided with a bevel gear 90', meshing with a bevel gear 91', on a shaft 92', and a gear 16, is provided on said shaft 92', which meshes with the gear 12', as shown in Figs. 3 and 16. Said shaft 15', is provided at its outer end with a bevel pinion 17', which meshes with a corresponding bevel pinion 18', which drives the veeder or other suitable register 19', secured at the top of the frame plate.

As shown, the machine is designed to register pennies, nickels and dimes, and for this purpose, as shown, counting stations are provided around the periphery of the carry-

ing wheel, indicated by 20', 21' and 22', respectively, being appropriated to nickels, pennies and dimes respectively.

Referring first to the mechanism for registering nickels or five cent pieces:—23', indicates a frame or bar rigidly secured on the frame plate and extending upwardly. Journaled in the lower part of said bar or frame and closely adjacent the frame plate is a shaft 24' provided at its outer end with a star wheel 25', having five hooked teeth thereon, which project through a slot in the frame plate beyond the periphery of the carrying wheel. At its opposite or inner end said shaft is provided with a bevel pinion 27' which meshes with a corresponding bevel pinion 28', driving a shaft 29', on which is a mutilated gear 30', as shown, provided with five teeth arranged at equal distances apart and projecting into position to mesh with a pinion 31', journaled on said beam or bar 23'. Said pinion 31', meshes with the master gear wheel 12', so that as said mutilated gear is revolved the pinion 31' is intermittently rotated in turn characteristically rotating the master 12', and thence the accumulating shaft 15' of the veeder 19'. Set in advance of said star wheel, is a guide plate 32', secured on the main frame plate and projecting over the channel or passage for the coin and to the periphery of the carrying wheel and serving to hold the coin down after the periphery thereof engages the star wheel and in the construction shown the machine being designed to count nickel fares, each nickel passing beneath the guide 32', and engaging the star wheel 25', of necessity rotates the shaft 24', one fifth of a revolution. In consequence, the mutilated gear 30', is provided with five teeth spaced equal distances apart, each of which serves to rotate the pinion, master gear and accumulator shaft sufficiently to mark up one fare on the veeder.

A brake is provided on the counting shaft 110 to obviate any inaccuracy on account of momentum. Secured on the shaft 24', is a five pointed star wheel 33', as shown in detail in Fig. 18, and mounted upon the frame bar 23', is a spring pressed arm 34', provided with a roller 35', at its lower end which at all times engages the star wheel 33', and which serves as a brake therefor, and owing to the deep indentations between the teeth of said star wheel 33', serves to instantly lock the same from further movement after it has been thrown characteristically by the mutilated gear.

Slightly at the rear of the nickel registering mechanism is the penny recorder, said coin being the next smaller size of coin after the nickel. As shown, said penny recording mechanism is supported upon a frame bar, corresponding with the frame bar 23', and beneath which and adjacent the frame plate 130

is journaled a shaft substantially identical in all particulars with that before described with reference to the nickel counting shaft and on the outer end of which is a star wheel 37', in advance of which is a guide plate 96', similar to the guide plate 32', before described, but which permits pennies and dimes to pass beneath the same.

The mutilated gear 39', on the penny shaft is provided with but a single tooth (see Fig. 3), inasmuch as the star wheel is provided with five teeth as before described, in consequence, necessitating an entire revolution of the shaft to count five cents upon 15 the veeder, or, in other words, to actuate the master gears to register or count upon the veeder. Said shaft is short and the star wheel 37', is arranged closely to the periphery of the carrying wheel and is designed to 20 intercept only the pennies presented thereto by the carrying wheel and to permit dimes to pass without registering thereon.

In a like manner to that before described, a brake such as shown in Fig. 18, is provided 25 to hold said shaft from throw or incorrect movement because of the momentum of the mechanism.

Next adjacent the penny registering mechanism and at the rear thereof is the mechanism for registering dimes. This is identical 30 in all respects with the counting mechanisms just described and is likewise provided with a five pointed star wheel 40', on the outer end of a shaft corresponding with the shaft 35 24'. Said shaft is also provided with a star brake wheel and detent lever such as before described and illustrated in Fig. 18.

The drive for the dime registering mechanism is identical to that before described 40 with the exception that the mutilated gear 47', provided with five teeth spaced equal distances apart meshes with a pinion 48', on a shaft 48a, and rigidly secured on said shaft is a larger pinion 49', which meshes with the 45 master gear 12'. The relative size of the pinions 49' and 48' are as two is to one, so that although the shaft is rotated by one fifth of a revolution by a dime passing beneath the guide 21, and engaging the star wheel 37', nevertheless, owing to the arrangement of the two to one gears as before described, each dime causes a rotation of the master gear twice as great as occasioned by each nickel in registering, and in consequence, records two fares upon the accumulating veeder. To obviate the possibility of 50 an additional coin finding its way into a pocket, a spring controlled pivoted stripper arm 84', is suitably engaged in a recess in the plate 2' of the carrying wheel and to permit any coin singly carried in a pocket of the carrying wheel to pass beneath the same and to engage any excess coin in any pocket in the periphery and strike the same 55 back into the hopper 66'.

The particular mechanism of the counting registering fare register affords no essential part of the present invention inasmuch as obviously the registering fare box may be used in combination with any counting 70 registering fare register to afford the double record constituting one of the important features of this invention. Said counting and registering fare register is mounted as is usual on a base 9, containing an automatically locking drawer to receive the coin after the same have been counted and registered by the counting register, and rigidly supported thereon and locked thereto is a casing 10, which may be constructed of cast 75 metal or any suitable material to afford a secure protection for the inclosed mechanism.

Supported upon the top of the counting register is the registering fare box, the 80 mechanism of which is also inclosed within the casing 10, and communicating with which through the top of the casing and rigidly secured on said casing is a coin receptacle embracing metallic posts 11, secured upon said casing and engaged between 85 which are sheets of glass 12, or other suitable transparent medium to permit the contents thereof to be at all times inspected.

Secured in, and closing the top of the coin 90 receptacle is a hopper 13, which may be of transparent or any suitable material and opening downwardly through the center thereof is an aperture 14, adapted to receive the coin, and secured to inclose said hopper 95 and supported in the coin receptacle beneath the same is a tortuous coin tube also of transparent material and comprising side sheets 15, of celluloid, glass or other suitable material between which are engaged 100 strips 16, of any suitable material, which are arranged obliquely and substantially in parallel relation between the side plates 15, to afford a tortuous passage.

As shown, one of the bottom inclined side 105 members 17, extends into said passage and is serrated or toothed, as indicated in Fig. 6, and as shown, a door plate 18, is pivoted on the upper member of said chute and depends to close the chute, and as shown, is also serrated, as indicated in Figs. 4 and 5, to mesh with corresponding serrations or teeth 19, on the bottom member 20, of said chute. Said door is pivoted so as to be normally closed, but the impact of a coin sliding down the 110 chute and striking the same serves to swing the door open to allow the coin to pass, immediately closing again thereafter. The object of this arrangement is to prevent a coin once dropped into the fare receptacle, from 115 being withdrawn by any instrument or device lowered through the coin tube to engage a coin without first injuring or destroying the coin tube.

At the bottom of the fare receptacle is the 120

fare registering mechanism and the mechanism for affording an audible signal and immediately at the bottom of said fare receptacle and affording a part of the top of 5 the casing for said registering and signaling means is a horizontal sliding door or shutter 21, adapted to be moved laterally to permit the discharge of the coin from the fare box to the counting means below the same.

10 As shown, a shaft 22, in alignment with the aperture through the outer wall of the casing, is adapted to be engaged by a crank 23, inserted therethrough to rotate or partly rotate the same, and as shown, said shaft 15 extends inwardly through the wall 24, of the fare register box and through a suitable bearing 25, integral therewith and at its inner end has rigidly engaged thereon a lever 26, which extends upwardly and is 20 longitudinally slotted at its upper end to engage a pin 27, set in the downwardly directed lugs or brackets 28, on the under side of said sliding shutter 21 so that when the crank is pulled, said sliding shutter 25 is actuated. As shown, a torsion spring 29, is secured at one end on said lever and at the other end on the bearing 25, so that after each actuation of the crank, said spring acts to immediately return the parts to normal 30 and close the shutter and mechanism is also provided whereby each actuation of the crank or lever 23, in opening the shutter also records the fare and sounds an audible signal.

35 For the purpose of affording an audible signal a bell 30, is secured on one wall of the fare register receptacle and the hammer 31, thereof is pivotally secured upon one of the wall plates of said casing and is provided with a strong spring 32, which acts 40 normally to hold said hammer or clapper in contact with the face of the bell. Secured on said lever 26, is an arm 33, having a shoulder thereon which engages at all times 45 a stud or arm 34, on the bar to which the hammer is secured, so that when said lever is actuated the hammer is elevated against the tension of the spring 32, with the effect of instantly returning said hammer to normal when released and also of striking a 50 blow upon the bell. Each actuation of the lever is also indicated on the register 35. This, as shown, is secured upon a bracket 36, on the outer side of the frame plate 38, for the fare box register and secured on the 55 shaft 90 of said register (which, as shown, is of the veeder type), is a ratchet wheel 39, which is held from reverse rotation by means of a pawl 70. Slidably engaged in a 60 bracket 40, adjacent said shaft 22, is a carriage 72 to which is pivoted a pawl 41, provided with a downwardly directed inwardly inclined extension 42, which engages behind a pin 43, set in said bracket. As shown

also a spring 44, is engaged on said bracket 65 and engages behind said pawl and acts to force the top thereof toward the ratchet so that in its elevated position with the lower end thereof engaged against the pin 43, any downward movement of the pawl serves to 70 actuate the ratchet one notch. Said pawl at its upper end is provided with a horizontal pin 45, directed toward the frame plate 38, and which is engaged in a longitudinal notch in an arm 46, secured on the shaft 22, 75 so that with each actuation of said shaft said pawl is drawn downwardly to rotate the ratchet 39, and consequently the units wheel on the veeder, (which is on the same shaft therefor) one notch or space indicating a 80 unit or digit on the counter or register. As shown also, a star wheel 47, is secured on said veeder shaft and pivotally secured to said bracket 40, is a spring pressed depending pawl 48, which serves as a brake to the 85 veeder shaft to overcome the momentum thereof when actuated to prevent more than the desired number registering. As shown, the veeder or register 35, is wholly concealed within the inclosing case 10, as is also the 90 register 8, for the counting mechanism and, for the purpose of enabling the register 35, to be inspected when necessary, a door 49, is provided in the casing directly opposite said registering mechanism 35, and the 95 mechanism for actuating the same.

Of course, it is important to provide means for locking the registering mechanism when the door is open. For this purpose, as shown, a bent lever 50, is pivotally 100 engaged between said door and said pawl 41, with the lower end thereof directed substantially horizontal toward and extending in close proximity to the lower end of the pawl and with the other end thereof extended substantially horizontally outward and adapted to bear against a striking block 60, when the door is closed, said lever or dog being so proportioned that when the door is closed, as shown in Fig. 12, the lower 110 end of said lever is swung away from the pawl to permit the same to slide up and down upon the pin, or, in other words, for the pawl to engage the ratchet wheel 39. When, however, the door is open the spring 115 51, swings the lower end of said lever inwardly to force the lower end of said pawl inwardly, thereby carrying the same a sufficient distance from the ratchet to prevent engagement therewith should the crank or 120 lever be actuated.

An inclined floor 53, is provided beneath the shutter 21, opening from the fare receptacle so that as the coin fall from the fare receptacle, they slide therefrom by gravity 125 into any suitable hopper or receptacle 66, positioned to deliver said coin to the carrying wheel 2, for the mechanical counting

mechanism. Should it occur, however, (as it sometimes does) that a foreign object is dropped into the receptacle, and which might possibly clog the counting mechanism, this may be permitted to drop away from the mechanical means by opening a door 54, provided in said inclined floor, 53, thus excluding the same from the receptacle delivering to the carrying wheel. Said door, 10 as shown, is hinged at its lower edge to a shaft 55, which extends outwardly through the casing 10, and is provided at its outer end with a milled or other suitable head 56, adapted for manual engagement, and a 15 spring 76, is secured to the shaft and is adapted to return the shaft to normal after each actuation.

As shown, supported on the wall of said hopper 66' and the face of the carrying 20 plate 2', are chutes corresponding in number with the number of dimensions of coin to be handled by the machine, and in this instance, indicated respectively by 67', 68' and 69' and appropriated in the order named 25 for nickles, pennies and dimes. Said chute comprises bottom and top plates. As shown, the bottom and top plates of said chutes 70' and 71 respectively are each constructed of a single plate of metal of which the top plate 30 71', is materially longer than the bottom plate. Said chutes are arranged as shown in Fig. 16 to overlie the carrying wheel with the mouths of said chutes directed downwardly, to respective compartments in the 35 drawer 9.

The operation is as follows: Registering devices such as embodied in the present invention are used more frequently on "Pay-as-you-enter" cars, and the registering mechanism is thus conveniently placed with reference to the collector or conductor. As the fares are received and deposited one by one in the fare receptacle, the collector with the deposit of each, pulls the lever 23, thus one 40 by one the coins pass down the tortuous coin chute, fall upon the sliding door 21, and with the pull of the lever 23, the audible signal is sounded by the bell 30, and the pawl 41, is reciprocated by the lever 46, on the shaft 22, with the effect, of registering each coin upon the register 35, therefor. With the actuation of the lever 26, the sliding door at the bottom of the coin receptacle is moved laterally to permit the coin to fall 45 upon the inclined floor 53, that is, to fall by gravity into any suitable hopper or receptacle 66' as shown in dotted lines in Fig. 2, at the lower edge of the inclined coin carrying wheel and the coins are taken up selectively in the periphery of said wheel and swept upwardly. Arranged at the top of 50 said wheel at varying distances from the bottom of the pocket (dependent upon the diameter of the coin of the respective de-

nomination), are the elements whereby the 65 counting register is actuated and indicated by 25', 37', and 40'. These are actuated selectively by the coin of the denomination to which appropriated and in turn these by appropriate mechanism rotate the gear 12', 70 to the denomination of the coin, this in turn transferring to the shafts 15 and 15^a, and to the registering mechanism 19'. Thus a double register is afforded for the fares collected. In each instance the conductor or collector is unable to see if or not the registers 75 coincide in communicating the same number of fares collected, and, inasmuch as the record is wholly concealed from view, and, inasmuch as a double check is kept upon the 80 collection, the collector, even though dishonestly disposed, fears to attempt any interference with the mechanism because of the certainty of one or the other of the mechanisms revealing the fact.

Should the conductor see a foreign object or a defaced coin has been delivered into the coin receptacle (which is readily noticeable from the sides thereof inasmuch as the chutes are transparent) he may discharge the same 90 by rotating the stem or pintle 55, by means of the external head 56. This opens the trap door 54, and permits such object to fall therethrough into a receptacle prepared therefor. Of course, such actuation registers 95 upon the fare receptacle register and also rings the bell. However, although a discrepancy is thus effected between the register for the mechanical counting mechanism and the register in the fare receptacle, the 100 articles in said separate receptacles when counted should number the same as the excess on the receptacle registering above the number registered by the counting mechanism. In this way a perfect check is at all 105 times had of the work of the collector and successful dishonesty is impossible.

Of course, while we have shown the invention in combination with a particular counting registering mechanism, we do not desire 110 to limit the invention thereto for obviously another counting registering mechanism may be used with the same purpose and effect as the one shown and described. We therefore do not purpose limiting ourselves 115 otherwise than necessitated by the prior art.

We claim as our invention:

1. In a device of the class described a casing, registering mechanism, a rotatable shaft, a plurality of arms secured thereon, 120 means operated by one thereof to discharge the coins to a receptacle and a sliding pawl operated by another of said arms to actuate said registering mechanism.

2. In a device of the class described a casing, a sliding plate to receive the deposited coin, a spring controlled oscillatable shaft, arms thereon, one adapted to operate said

- sliding plate to discharge the coin, a slidably mounted pawl operated by another of said arms, and registering mechanism actuated by said pawl.
- 5 3. In a device of the class described a casting, a spring controlled oscillatable shaft journaled therein, a slidable shutter and slidable pawl, arms on the shaft to actuate each, the one to discharge the coin, the other 10 to actuate the pawl, and registering mechanism operated by said pawl.
4. In a fare register a slidable element, a shaft journaled in said fare register, registering mechanism, a slidable carriage, means 15 on said shaft to move said carriage, a pawl pivoted on said carriage, a ratchet wheel connected to said register mechanism adapted to be driven by said pawl when said carriage is moved to cause registration of the 20 fare as the fare is discharged by said slid- able element, and means connected to said registering mechanism to limit the movement thereof to one count for each actuation of said element.
- 25 5. In a device of the class described concealed registering mechanism normally in actuating position, a door in the device to permit access to said mechanism, and means adapted to throw said registering mecha- 30 nism out of actuating position when said door is opened.
6. A fare register comprising a slidable element to permit passage of coins therethrough, a shaft extending through said 35 fare register, a crank thereon to actuate said element, a spring actuated arm pivoted on said crank, bell mechanism operated thereby and registering mechanism adapted to be operated with each actuation of said shaft.
- 40 7. A device of the class described embrac- ing a transparent fare box to receive the fares, a sliding bottom therefor adapted to be manually actuated to discharge the coin therethrough, mechanism for actuating 45 the same, a registering mechanism, an audible signal, both connected to be operated simultaneously with the movement of said sliding bottom, an inclined floor beneath said sliding bottom adapted to discharge the 50 coins by gravity therefrom, and a door in said floor adapted to be manually opened to permit the discharge of defective coin or foreign objects therethrough.
8. A device of the class described embrac- 55 ing a transparent fare box to receive the fares, a sliding bottom for permitting discharge of the coin therefrom, a registering mechanism, a bell, mechanism for simultaneously actuating the sliding bottom, the 60 registering mechanism and the bell, an inclined floor beneath said sliding bottom adapted to discharge the coins by gravity therefrom, a door in said floor adapted to be opened to permit the discharge of defec- tive coin or foreign objects therethrough and a shaft for opening said door.
9. In a fare register mechanical coin carrying means, a register operated by the coins thereon, a counter adapted to be manu- 70 ally actuated by the collector as the fares are deposited, a casing inclosing said register and counter, a door in said casing to permit the collector to inspect the counter, and means for disentaining said counter simultaneously with the opening of the 75 door.
10. A device of the class described embrac- 80 ing a fare box, a sliding bottom for permitting the discharge of coin therefrom, a registering mechanism, a bell, mechanism for simultaneously actuating the sliding bottom, the registering mechanism and the bell, a casing inclosing said registering mecha- 85 nism, a door in said casing to permit inspection of the registering mechanism and means acting to disconnect the registering mechanism to prevent actuation, simultaneously with the opening of the door.
11. In a fare register a fare box to receive the coin, counting and sorting mecha- 90 nism for the coins, mechanism for discharging the coins from said fare box to said coin counting and sorting mechanism, a sliding carriage, a pawl pivoted thereon, said carriage adapted to be moved by said discharg- 95 ing mechanism, a ratchet wheel adapted to be actuated by said pawl, and a register connected with said ratchet wheel to count the actuations of said discharge mechanism.
12. In a fare register a fare box to receive the coin, registering and counting mechanism for the coins, means adapted to be opened to permit discharge of the coins from said fare box to said counting and 100 registering mechanism, a lever for actuating said opening means, registering mechanism connected for counting the number of actuations thereof, and means automatically dis- entraining the counting registering mecha- 105 nism when access is gained thereto.
13. In a fare register means to receive a coin, counting and registering means for the coin, mechanism controlling the discharge from said receiving means to said counting and registering means, a lever 110 forming a part thereof, a sliding carriage actuatable thereby, a pawl pivoted on said carriage, a ratchet wheel driven by said pawl, and a register connected to said ratchet wheel to count the number of actua- 115 tions thereof.
14. In a fare register a fare box to receive the coins, counting and sorting mecha- 120 nism for the coins, mechanism for discharg- 125 ing the coins from said fare box to said counting and sorting mechanism, a vertically slid- able carriage, a pawl pivoted thereon, means moving said carriage sim-

taneously with movement of said discharging mechanism, a ratchet wheel adapted to be actuated by said pawl, and a register connected with said ratchet wheel to count the actuations of said discharging mechanism.

In testimony whereof we have hereunto

subscribed our names in the presence of two subscribing witnesses.

JAY M. JOHNSON.
HUGO J. BAUR.
